UNITED STATES PATENT OFFICE.

WALLACE F. MACGREGOR, OF RACINE, WISCONSIN, ASSIGNOR TO J. I. CASE THRESHING MACHINE COMPANY, OF RACINE, WISCONSIN, A CORPORATION.

THRESHING-MACHINE.

1,096,547.

Specification of Letters Patent. Patented May 12, 1914.

Application filed July 7, 1905. Serial No. 268,645.

To all whom it may concern:

Be it known that I, WALLACE F. MACGREGOR, a citizen of the United States, and a resident of Racine, county of Racine, and 5 State of Wisconsin, have invented certain new and useful Improvements in Threshing-Machines, of which the following is declared to be a full, clear, and exact description.

10 The invention relates to the frame or casing of the threshing machine and seeks to provide a frame formed of structural metal bars which will be comparatively light in weight, but which is so arranged that great 15 rigidity and strength is given to the structure and in which provision is made for properly supporting the different operating parts of the machine.

The invention consists of the features of 20 construction, combinations and arrangements of parts hereinafter set forth, illustrated in the accompanying drawings and more particularly pointed out in the appended claims.

25 In the drawings Figure 1 is a side view of the improved frame or casing. Fig. 2 is a longitudinal section thereof. Fig. 2^a is a detail front view. Fig. 3 is a cross section on line 3—3 of Fig. 1 omitting the straw carrier and grain pan. Fig. 3^a is a detail perspective view of one of the filler blocks. Figs. 4 and 5 are partial sections of the 30 side wall and deck respectively taken on line 5—5 of Fig. 1. Fig. 6 is a detail section on line 6—6 of Fig. 3. Fig. 7 is an enlarged detail view illustrating the manner in which certain of the operating shafts are supported from the main and sub-sills. Fig. 35 8 is a detail perspective view of one end of the shaft supporting brace bar. Fig. 9 is an enlarged detail view illustrating the connection between the rear end of the main sill and sub-sill. Fig. 10 is a detail view showing the construction of the rear axle.

40 In prior constructions employing a wood frame, the sills of the machine have been formed in separate sections. The rear sections of the sills were disposed just above the rear axle and extended forwardly therefrom beneath the grain-cleaning devices to a point about mid-way between the ends of the machine. The forward ends of these sill sections were connected by a reach to the bolster of the front axle. The front sill sections were elevated above the rear sill sec-

tions and extended rearwardly from the front bolster to a point over the front ends of the rear sill sections. The overlapping ends of the front and rear sill sections were connected by suitable struts.

In the present improved frame the main sills 10 which are preferably formed of steel channel-bars, are continuous and extend from front to rear of the machine. These main sills are elevated above the front and rear axles and above the grain-cleaning devices. The uprights of the frame formed of suitable structural steel bars, are rigidly secured to the sills 10 and the two rear pairs of uprights 11 and 12 depend below the 65 same as shown. Beneath the rear ends of the main sills 10 are arranged the short sub-sills 13 which are rigidly secured to the lower ends of the rear uprights 11 and 12. The rear axle is secured to the sub-sills 13. 70 Inclined strengthening brace-bars 14 are connected to the front ends of the sub-sills 13 and at their lower, rear ends, and their front, upper ends are connected to the main sills 10 near the forward ends thereof, but in rear 75 of the connections between the main sills and the front axle. Connecting bars 15 depend from the forward ends of the main sills 10 to the bolster of the front axle. In the construction described, the weight of the 80 machine and the thrust as the machine is drawn forward or back, is largely taken on the continuous main sills. This construction obviates the necessity of employing any 85 strengthening reach between the front and rear axles and the front wheels may therefore be turned completely under the machine to turn sharp corners or for shipping.

The main sills 10 as stated, are preferably formed of channel bars, the flanges of which 90 are turned outwardly (see Fig. 3). The sub-sills 13 are also formed of channel bars having outwardly turned flanges and are arranged directly beneath the main sills 10 (see Fig. 4). The extreme rear and 95 extreme forward uprights 11 and 16 are preferably formed of angle bars while the intermediate uprights 12, 17 and 18 are formed of T-bars. All the uprights have their 100 flanges turned outwardly as shown, and are bent over and secured to the outer faces of the main sills and the lower ends of the two rear uprights 11 and 12 are bent over and 105 secured to the outer faces of the sub-sills 13. To afford a firm bearing for the uprights 110

at their connections with the main and sub-sills, filler blocks 19 (see Figs. 3, 3^a and 4) are arranged within the channel-bar sills 10 and 13 opposite the uprights, and these blocks are provided with openings through which the connecting bolts or rivets 20 extend. The uprights are all bent as shown, so that their flat, inner faces are in line or in the same plane with the inner faces of the sills. Longitudinally extending deck supporting bars or beam 21 are connected to the upper ends of the uprights and these beams are preferably formed of steel angle bars with outwardly facing flanges. The upper ends of the uprights are also preferably bent outwardly, as shown in Figs. 3 and 4, to bring the inner faces of the bars 21 in line with the inner faces of the uprights and sills. By this arrangement the thin plate metal sheathing 22, which forms the walls of the inclosing casing of the machine, may be conveniently bolted or riveted to the inner faces of sills 10 and 13 and to the inner faces of uprights 17 and longitudinally extending bars 21. That is to say, the plates do not have to be bent or shaped to fit in place but, what is more important with this arrangement, the interior walls of the casing are devoid of any obstructions which would interfere with the proper passage of the straw through the machine. At the same time by bending the uprights outwardly over the sills and the deck bars, rigid connections can be secured between these members of the frame without in any way weakening them.

The plate metal sheathing 23 (see Fig. 5), which forms the deck of the machine or top of the inclosing casing therefor, rests upon and is bolted or riveted to the horizontal outwardly projecting flanges of the deck bars 21. Preferably as shown in Fig. 5, these deck plates slope or are inclined downwardly from the center line of the machine at a slight angle to the horizontal and their edges extend beyond the bars 21 and terminate in downwardly turned lips 24. By this arrangement rain will quickly drain from the deck of the machine and cannot enter the casing at the joint between the side walls and top thereof.

Transverse strengthening deck beams 25 are bolted or riveted to the sheathing 23 and to the longitudinally extending deck bars 21. These transverse deck beams are preferably formed of T-bars, the flanges of which project upwardly and these deck beams are also preferably arranged in line with the uprights 12, 17 and 18 so that the weight of the deck is borne on the uprights. A central, longitudinally extending T-bar 26 extends along the under side of the deck sheathing 23 at its central portion, and is secured thereto and to the transverse deck beams 25 by bolts or rivets. Preferably also,

longitudinally extending angle bars 27 are secured to the under side of the deck sheathing and to the transverse beams 25. These bars 27 are located as shown, mid-way between the center and sides of the casing.

The angle bars 27 do not extend between the pairs of uprights 17 and 18, and 16 and 18 at the forward part of the machine, and the deck is preferably formed, at these points, of removable slides 28 so that access is afforded to the interior of the casing and to the beater and forward end of the straw rack. The central longitudinal deck bar 26 between the uprights 17 and 18, and 16 and 18, is provided with the strips 29 and 30 (see Fig. 3) which are bolted or riveted to the upper face thereof. The edges of the lower strip 29 are bent downwardly to form spaces which receive the inner edges of the slides 28. The side edges of the slides 28 abut against the edges of the T-bar deck beams 25 (see Fig. 6), and are held in place and guided by strips 31 and 32 secured to the flanges of the T-bars. This arrangement of guide strips prevents any leaking at the edges of the slides. The outer edges of the slides are provided with downturned lips 24' which correspond to the lips 24 of the stationary deck plates. These lips also form a convenient handle by which the slides may be moved to and from position.

The sub-sills 13 are secured to the lower ends of the rear uprights 11 and 12, as described. Each is also connected to the lower end of a heavy U-shaped brace bar 33, the legs of which diverge upwardly and are bolted to the lower flange of the main sill 10. The lower portion of the brace is bolted to the upper flange of the sub-sill 13 just above the rear axle. The rear axle is formed of two channel bars 34 with their flanges facing inwardly toward each other. The journal pieces 35 upon which the wheels 36 are mounted, are secured in place between the channel bars 34 by bolts 37, which also secure the separate channel bars of the axle together. The axle is secured at each end to the sub-sills by bent straps 38, which extend beneath the same and which are bolted to the lower flange of the sub-sill, and by a bolt 39, which extends through the straps 38 and journal pieces 35, and also through the flanges of the sub-sill and through the brace-bar 33. The sub-sills are further braced by cross lattice bars 40, which extend diagonally from each end of the sills and by a cross angle-bar 41 extending between their rear ends. The forward ends of the sub-sills 13 project in front of the lower ends of the uprights 12 and are secured to the lower rear ends of the inclined brace bars 14 by bolts 42. The lower ends of the brace bars are bent to horizontal position, as shown most clearly in Fig. 7, so as to rest properly upon the upper flanges of the sub-

sills. These brace bars are preferably formed of heavy angle-bars with one of its flanges projecting upwardly and the other outwardly, as shown. At the upper, forward end of each bar, the upwardly projecting flange is bent over into engagement with the outwardly projecting flange, as shown in Figs. 7 and 8, and the bolts 43 which connect the end of the brace-bar to the lower flange 5 of the main sill 10 extend through this lapped portion so that the brace-bar is not weakened at its point of connection with the main sill. The intermediate uprights 17 extend below the main sill 10 to the inclined brace-bars 14, and are secured to the upwardly extending flanges thereof, as shown in Fig. 7.

The forward uprights 16 extend below the main sills 10 and are connected by a heavy cross angle-bar 44. The extreme front ends of the main sills are connected by a channel-bar 45. The connections between the main sills and front axle are preferably in the form of angle-bars 15 bent to U-shape, their upper divergent ends being secured to the angle-bar 44 and the cross channel-bar 45. The lower ends of the connections 15 incline toward each other and are bolted to a bolster or head 46 which is provided with a ball-shaped lower end fitting within a socket 47 of cast metal. This socket is bolted between the channel-bars 48, which form the front axle. Journal pieces secured between the channel-bars 48 carry the front wheels 50. The pole 51 is rigidly secured to the axle.

It will be noted that the center of the ball and socket is slightly in the rear of the center of the journals for the wheels so that the weight of the machine tends to balance the pole which is usually long and heavy. This particular arrangement forms the subject-matter of another application and is not claimed herein. But the arrangement 40 of the connections for the front axle obviates the necessity of any king bolt or bracing reach therefor. Moreover, the arrangement of the continuous main sill obviates the necessity of any reach for connecting the front and rear axles. In this construction the thrust or draft upon the pole is transmitted through the forwardly and rearwardly inclined connecting pieces 15 to the front end of the main sill 10, and the draft 45 is transmitted by the main sill and by the inclined brace-bars 14 to the sub-sill 13 and the rear axle. By doing away with the reach the weight of the machine is considerably reduced and the front wheels may be turned under the machine. Indeed, with the form shown, the front wheels may be turned through a complete half circle to bring the pole beneath the machine and thereby considerably reducing the amount 50 of car space required in shipping.

Upon the forward ends of the main sills 10 and in front of the upright 16 of the main casing, is arranged a supplemental casing 52, the sides of which are formed of heavy plates having upright and horizontal projecting ribs 53 and 54. These plates are secured to the ends of the sills by bolts extending through the lower horizontal rib 54 and the upper flange of the sill. The journal boxes 55 for the cylinder shaft 56 are 55 secured to the upper horizontal rib 54 of the casings. This shaft carries the threshing cylinder 57. In rear of the cylinder is a cross angle-bar 57' extending between the uprights 16. A sheet metal baffle 57'' depends from the deck and its lower edges folded about the bar 57'. In rear of the baffle is arranged a beater 58 mounted upon a transverse horizontal shaft 59. This shaft projects through the sheathing or side walls 60 of the machine casing and is journaled in boxes 60 which are secured to and supported upon the outwardly projecting horizontal flange of the short angle-bars 61. The ends of these bars overlap the flanges of the 60 uprights 16 and 18 and are bolted thereto. In order that the beater may be easily removed for repairs and the like, the sheathing opposite the beater is provided with a circular opening which is closed by a circular plate 62 removably bolted in place. The transverse bar 61 extends across the plate 62 and its ends are however removably secured to the uprights 16 and 18. By removing the bolts which hold the plate 62 70 and bar 61 in place, the beater cylinder can be readily taken from position for repairs or the like.

The straw rack 63 and grain conveyer 64, together with its sieve 65, extend longitudinally through the casing and are hung, in the usual manner, upon arms 66 which are carried upon the rock shafts 67. In the form shown the arms 66 are connected to the shafts intermediate their ends and the straw 75 rack 63 is pivoted to the upper ends of the arms while the conveyer and sieve are pivotally connected to the lower ends thereof. The ends of the shafts 67 are journaled in boxes 68 which are supported upon and connected to the upper flange of the main sills 10. Plate metal slides 69 are arranged in the sides of the casing opposite the boxes 80 68 so that access is afforded to the interior of the machine at the points of support for 85 the straw rack and conveyer. The arms 66 on the front rock shaft 67 are provided in the usual manner with the depending extensions 70, which are connected by pitmen 71 to the cranked shaft 72, which is rotated in 90 any suitable manner to reciprocate the straw rack and conveyer. The ends of the drive shaft 72 are journaled in boxes 73 which are secured to the lower, horizontal flange of the shaft supporting brace-bars 14 near the 95 100 105 110 115 120 125 130

forward ends thereof. Brace straps 74 are connected to these boxes and the two lower flanges of the main sills (see Fig. 3), so that the operating shaft is securely supported. The brace-bars 14 also serve to support the journal boxes 75 of the fan shaft 76, and journal boxes 75' of the shoe operating shaft 76'. These boxes are secured to the brace-bars between their ends. Shaft 76 carries the grain-cleaning fan 77, the casing 78 of which is secured to the main sills and to supporting brace-bars 14 and at its forward portion is connected to cross bars 79 which extend between the inclined brace-bars 14. At its rear portion, the fan casing is connected to cross bars 80, and to the forward edge of the sheet metal casing 81 of the grain auger. The rear edge of the grain auger casing is secured to a cross angle-bar 82. The cast metal heads 83 of the auger casing (which are shown in section in Fig. 7) are provided with projecting lug-ports 84 which fit snugly against the lower, horizontal flange of the brace-bars 14 and are securely bolted thereto. The shaft 85 of the grain auger is journaled in brackets 86 (see Fig. 1) secured to the cast metal heads 83.

The bottom of the fan-casing between the angle-bars 79 and the angle-bars 79' (which are secured thereto at its rear portion) may be removed to afford access to the fan-casing. In this manner, the bars 14 not only serve as suitable braces between the main and sub-sills, but also serve as common supporters for the operating shaft 72, the fan shaft 76, the shoe-operating shaft 76' and the transverse grain auger.

The fan casing is preferably provided with sheet metal slides 87 mounted in guides 88, so that access may be afforded to the interior of the fan casing and so that the blast may be regulated.

The shoe 80' is carried on spring supports 81' below the sieve 65 and is connected to the shaft 76' by pitmen 82'. The shoe 80' delivers the grain into the auger casing 81. The sheet metal casing 90 of the tailings auger is secured to cross angle-bars 90' which extend between metal heads 91 (see Fig. 1), each of which heads is provided with lugs 92 by which it is bolted to the rear upright 11. The shaft 93 of the tailings auger is journaled in the cast metal heads 91.

The stacker casing 94 (the front portion of which only is shown) may be of any suitable construction and is mounted upon a sill 95 which is connected by plates 96 to the rear projecting ends of the sub-sills 13. The front portion of the stacker casing is provided with angle-bar uprights 97 which abut against the rear uprights 11 of the thrasher casing, and is secured thereto by bolts 98. A strengthening transverse angle-bar 99 (see Fig. 2) extends between the rear uprights 11 of the thrasher casing between the straw

rack and conveyer sieve, and a bracing angle-bar 100 extends between the main sills midway between the ends.

The cylinder and beater shafts 56 and 59, the rack operating shaft 72 and fan shaft 76 may be driven in any suitable or well-known manner, as by means of pulleys and belts as indicated by dotted lines in Fig. 1.

It is obvious that changes may be made in the details of structure without departure from the essentials of the invention.

Having described my invention, what I claim as new and desire to secure by Letters Patent is:—

1. In a threshing machine, the combination with the out-turned channel-bar main sills, metal bar uprights secured to and bent over the outer face of said sills, filler-blocks in said channel bars against which said uprights abut and through which the connecting bolts extend, the inner faces of said sills and upright being in the same vertical plane and sheathing secured to said faces, substantially as described.

2. In a threshing machine, the combination with the out-turned channel-bar main sills, of the T-bar uprights secured thereto and bent over the outer faces thereof, filler blocks between said sills and uprights, longitudinal angle-bars secured to the upper ends of said uprights, the inner faces of said sills, uprights and bars being in the same plane and plate metal sheathing secured to said faces, substantially as described.

3. In a threshing machine, a structural metal frame comprising the out-turned channel-bar main sills, T-bar uprights secured thereto and bent over the outer faces thereof, longitudinal angle bars connecting the upper ends of said upright, the inner faces of said sills, uprights and angle bars being in the same plane, plate metal sheathing secured to the inner faces of said sills and uprights, deck plates secured to the upper face of said angle bars, transverse T-bar deck-beams secured to the upper face of said deck plates and to said angle bars and longitudinal brace bars secured to the under face of said deck plates, substantially as described.

4. In a threshing machine, the structural metal frame therefor comprising the main sills, uprights secured thereto, longitudinal deck-bars secured to said uprights, plate metal deck plates secured to said longitudinal bars and inclined downwardly from the center of the deck, the edge of said deck plates extending beyond said bars and having downwardly turned lips, substantially as described.

5. In a threshing machine, the structural metal frame comprising the main sills, uprights secured thereto, longitudinal and transverse deck-bars secured to the upper ends of said uprights, slides arranged between adjacent transverse deck-bars, a cen-

- ter deck-bar secured to said transverse deck-bars and strips secured to said center and transverse bars overlapping the edges of said slides, substantially as described.
- 5 6. In threshing machines, the combination with the channel-bar main and sub-sills, uprights connecting said sills, and the inclined shaft-supporting angle bars connecting the forward end of said sub-sills to said main 10 sills, the flanges of said angle bars being bent together at the point of connection thereof with said main sills, substantially as described.
- 15 7. In a threshing machine, the combination with the front and rear axles, of a structural metal frame supported at its forward end on said front axle and comprising horizontal channel bar main sills, short channel bar sub-sills below the rear ends of 20 said main sills connected to the rear axle, the flanges of said main and sub-sills being out-turned, metal bar uprights secured to said main sills, the rear uprights being continuous and extending both above and below said 25 main sills and having their lower ends secured to said sub-sills, said uprights having outturned flanges and being bent over the outturned flanges of said main and sub-sills and having their inner faces in substantially 30 the same vertical plane with the inner faces of said main and sub-sills, means to inter-connect the upper ends of said uprights, and plate metal sheathing secured to the inner faces of said main sills, uprights and sub- 35 sills.
8. In a threshing machine, the combination with the front and rear axles of a structural metal frame comprising main sills, inclined bracing connections depending from 40 the front ends of said main sills with the front axle, short, channel-bar sub-sills below the rear ends of said main sills and secured to the rear axle, inclined bracing connections secured at their upper ends to the rear ends
- of said main sills and at their lower ends to 45 said sub-sills and said rear axle, and inclined brace-bars connecting the forward ends of said main and sub-sills.
9. In a threshing machine, the combination of a sheathed frame including forwardly and rearwardly directed main sills at the sides of the machine, and relatively short sub-sills below the rear portions only of said main sills, inclined brace bars extending forwardly and upwardly from the 50 forward end portions of the sub-sills and connected at their upper ends with the intermediate portions of the respective main sills, transverse rock shafts journaled on the main sills, a straw rack and grain pan within the 55 frame and connected with said rock shafts, and an operating shaft for said rock shafts journaled on said inclined brace bars, substantially as described.
10. In a threshing machine, the combination of a sheathed frame including forwardly and rearwardly directed main sills at the sides of the machine, and relatively short sub-sills below the rear portions only of said main sills, inclined brace bars extending forwardly and upwardly from the 60 forward end portions of the sub-sills and connected at their upper ends with the intermediate portions of the respective main sills, transverse rock shafts journaled on the 65 main sills, a straw rack and grain pan within the frame and connected with said rock shafts, and an operating shaft for said rock shafts journaled on said inclined brace bars, substantially as described.
